UNITED STATES PATENT OFFICE.

JAMES L. RAY, OF ESSINGTON, PENNSYLVANIA, ASSIGNOR TO WESTINGHOUSE ELECTRIC & MANUFACTURING COMPANY, A CORPORATION OF PENNSYLVANIA.

TURBINE-BLADE FASTENING.

Application filed September 8, 1924. Serial No. 736,653.

My invention relates to turbines, more particularly to the blade-holding means thereof, and has for its object the provision of apparatus of the character designated which 5 shall be simple of construction and which shall securely hold the blades in place.

More specifically the object of my invention is to provide means, in a turbine having a blade-holding element with undercut 10 grooves, for securely fastening the last blade to be inserted in said groove.

Apparatus embodying features of my invention is illustrated in the accompanying drawings, in which: Fig. 1 is a fragmentary 15 plan view of a turbine rotor having blades secured therein in accordance with my invention; Fig. 2 is a fragmentary sectional view of the rotor showing a form of undercut groove; Fig. 3 is a sectional view along 20 the line III—III of Fig. 1; Fig. 4 is a sectional view along the line IV—IV of Fig. 1; Fig. 5 is a view similar to Fig. 4 showing a modified form of locking piece; Figs. 6 and 7 are perspective views of the locking pieces 25 shown in Figs. 3 and 5; and Fig. 8 is a view similar to Fig. 1, but illustrating a method of assembling the blades and locking pieces in the blade-holding element.

In the construction of elastic-fluid turbines 30 wherein the blades are secured in an annular undercut groove in the rotor, it is necessary to provide the groove with an enlarged portion of sufficient length to permit the insertion of one or more blades in order that the 35 blades may be inserted in the groove. The blades are then inserted through the enlarged portion of the groove, moved around the rotor and wedged in place. In completing the row of blades, difficulties have been encountered 40 in adequately securing the blade or blades in position which of a necessity are located in the enlarged portion of the groove.

In accordance with my invention I provide 45 the enlarged portion of the groove with notches along the sides and provide locking pieces for the blades having complementary 50 projections fitting the notched portion of the groove. The locking pieces are narrower than the blade root pitch, whereby they may 55 be inserted in the enlarged portion of the groove and still permit the insertion of a blade between them. The groove may be provided with a single notch along its side or preferably be provided with a plurality of notches or serrations in order to secure firm

engagement between the locking piece, the side of the groove and the blades. In assembling, the locking pieces are driven between the blade root and the side of the groove and wedge members are driven between the locking pieces, thereby providing a sturdy and 60 unitary structure. I prefer to machine the notches so that they extend in a direction normal to a radius of the blade-holding element intersecting therewith so that when the locking pieces are driven between the blade root and the side of the blade, they exert a radial force on the blade root inwardly of the blade-holding element.

Referring now to the drawings for a fuller 70 understanding of my invention I show in Figs. 1 to 4, inclusive, a blade-holding element such as a rotor at 10, said blade-holding element being provided with an undercut groove 11 for holding a row of blades 12. The undercut groove may be of the form shown in Fig. 2 or of any other form known to the art whereby the blade-holding element and blade are provided with cooperating surfaces for holding the blades in position and resisting 75 stresses due to centrifugal force. The blades 12 have root portions 13 conforming to the contour of the groove, or may have other forms, not shown, known to those skilled in the art. In order to insert the blades 12 in the 80 groove 11 it is necessary to provide a widened portion of the groove. To this end, I show at 14 a widened portion of the groove 11 for inserting the blades therein. The widened portion 14 is of sufficient length in this instance 85 to accommodate five blades, though it will be apparent that it might be of any length so long as one or more blades might be inserted therein.

The widened portion 14 of the groove 11 90 has its sides provided with notches 16—16. The notches 16 may be in the form of serrations as shown in Figs. 3 and 4, although there may be a single notch on each side of the groove as shown in Fig. 5. In order to secure 100 the blades in position in the groove 11, locking pieces 18, 19, 21 and 22 are provided, having one side with projections 20 corresponding to the notches in the side of the enlarged portion 14 of the groove 11 and having the other side with a contour conforming to the 105 contour of the blade root. Upon assembly, these locking pieces are driven from the outer ends toward the center line of the widened portion 14, as shown, between the blade root 110

and the side of the enlarged portion of the groove so as to hold the blades 12 in place in the groove.

In cutting the notches 16 I prefer to employ a milling cutter in order to secure a more accurate workmanship. In cutting the notches 16 in this manner, the enlarged portion 14 will be finished with circular ends as shown in Figs. 1 and 8. In assembling, 10 after the blade row has been completed except for those blades which are to be located in the enlarged portion 14, I first insert filling pieces 23 at the ends of the enlarged portion 14, said filling pieces having a quarter 15 round contour in section so as to fit the circular ends of the enlarged portion 14. I next insert the locking pieces 18, 19, 21, and 22, similar ones on each side, moving the locking pieces 18 and 19 as far to the left as possible 20 and the locking pieces 21 and 22 as far to the right as possible.

The locking pieces 18, 19, 21 and 22 are made narrower than the blade root pitch as may be seen from the assembly view in Fig. 8. 25 By making them in this manner and, upon assembly, inserting them in the manner just described, there is left between the locking pieces 19 and 21 just enough space P (Fig. 8) for the insertion of one blade. This construction permits the employment of an 30 undercut groove 11 (Fig. 2) in the rotor, which has been found very desirable for retaining turbine blades in high velocity rotors.

I next insert the blades through the space 35 P between the locking pieces 19 and 21, moving them to the right and left to their proper positions, finally inserting the last blade completing the row. The locking piece 19 is next moved to the right and the locking piece 21 40 to the left followed by the locking piece 18 being moved to the right and the locking piece 22 being moved to the left to the positions shown in Fig. 1. It will be seen by referring to Fig. 3 that by moving the locking 45 pieces in the manner just described the co-operating projections and notches of the locking pieces and the side of the groove engage and hold the blades in place. Wedge members 24—24 are next driven into the spaces 50 between adjacent locking pieces 18, 19, 21 and 22 and caulked over, thus providing a sturdy and unitary structure.

The locking pieces 18, 19, 21 and 22 inserted 55 on each side of the large portion 14 of the groove 11 may be similar or a part may be cut away at the top of the locking pieces to be inserted in one side of the groove as shown in Figs. 4 and 5 and wedges 26 driven between the locking piece and the blade root in order 60 to exert a lateral force against the side of the blade and more firmly holding it in engagement with the blade-holding element.

While the notches 16 may extend parallel 65 to the bottom of the groove 11, I prefer to so machine them that they extend in a

straight line so that upon assembly as previously described there is a radial as well as a lateral displacement of the locking pieces, whereby they exert a radial force upon the blade root inwardly of the blade-holding element. To this end I show the serrations 16 70 in Fig. 3 as extending in a direction normal to, and bisected by, a radial line 17 intersecting therewith. With the notches 16 cut in this manner and the locking pieces 18, 19, 21 75 and 22 in the positions shown in Fig. 8, when the locking pieces are moved to the right and left in the groove as described, there is a radial displacement of the locking pieces inwardly of the blade-holding element, forcing 80 the blades downwardly into the bottom of the groove 11.

From the foregoing, it will be apparent that I have invented an improved means for securing blades in the groove of a turbine 85 blade-holding element wherein the groove is wider than the root of the blade to be secured.

While I have shown my invention in but two forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims. 95

What I claim is:

1. In a turbine having a rotor, said rotor being provided with an undercut groove for holding a row of blades, said undercut groove having a widened portion for the insertion of blades therein, the combination of a turbine blade inserted in the widened portion, a locking piece narrower than the turbine blade root longitudinally of the undercut groove 100 and fitting the side of the blade root and the groove, and means for wedging the locking piece in engagement with the blade root and the groove.

2. In a turbine having a rotor, said rotor being provided with an undercut groove for holding a row of blades having roots fitting the sides of the undercut groove, said groove having a widened portion with notched sides for the insertion of blades within the undercut groove, a plurality of blades within the widened portion of the groove, a plurality of locking pieces for holding the blades within the widened portion, said locking pieces being narrower than the blade root longitudinally of the undercut groove and fitting the side of the blade root and the side of the groove, and means for wedging the locking pieces in engagement with the blade root and the widened portion of the groove.

3. In a turbine, the combination of a blade-holding element having a groove with notched sides, said notches extending transversely of the axis of rotation in a direction substantially normal to a radius of the blade- 125

holding element intersecting therewith, a blade within the groove, and locking pieces for holding the blade in position, said locking pieces having complementary projections fitting the notches of the groove.

4. In a turbine, the combination of a blade-holding element having an undercut groove with a row of blades mounted therein, said groove having for a relatively short distance 10 a portion wider than the blade roots for inserting the blades in the undercut groove, the sides of said widened portion being provided with notches extending transversely of the axis of rotation in a direction substantially 15 normal to a radius of the blade-holding element intersecting therewith, a blade within the widened portion, and locking pieces for holding the blade therein, said locking pieces having complementary projections fitting 20 the notches of the groove.

5. In a turbine, the combination of a blade-holding element having an undercut groove for holding the blades, said groove being widened for a relatively short distance for inserting the blades in the undercut groove, said widened portion having notched sides, a plurality of blades within the widened portion, locking pieces for holding the blades in place within the widened portion, said locking 25 pieces being in spaced relation to each other and having projections fitting the notches of 30 the groove.

6. In a turbine, the combination of a blade-holding element having a groove with serrated sides, said serrations extending transversely of the axis of rotation and in a direction substantially normal to a radius of the blade-holding element intersecting therewith, a blade within the groove, and a locking 35 piece having complementary serrations fitting the serrations of the groove, said locking piece adapted to be driven along the groove at the side of the blade in a direction for exerting a radial force on the blade root 40 inwardly of the blade-holding element.

7. In a turbine, the combination of a blade-holding element having an undercut groove for holding the blades, said groove being widened for a relatively short distance for inserting the blades in the undercut groove, the widened portion of said groove having serrated sides, said serrations extending transversely of the axis of rotation in a direction substantially normal to a radius of the blade-holding element intersecting therewith, a blade within the widened portion, and locking pieces for holding the blade in the widened portion, said locking pieces having complementary serrations fitting the serrations of the groove, and adapted to be driven between the side of the groove and the blade for exerting a radial force on the blade root 50 inwardly of the blade-holding element.

8. In a turbine, the combination of a blade-holding element having an undercut groove

for holding the blades, said groove being widened for a relatively short distance for inserting the blades in the undercut groove, the widened portion of said groove having serrated sides, said serrations extending 55 transversely of the axis of rotation in a direction substantially normal to a radius of the blade-holding element intersecting therewith, a plurality of blades within the widened portion, and locking pieces for holding the 60 blades in the widened portion, said locking pieces having one side conforming in contour to the blade root and the other side thereof having complementary serrations fitting the serrations of the widened out portion and 65 adapted to be driven between the blade and the side of the groove in a direction for exerting a radial force inwardly of the blade-holding element.

9. In a turbine, the combination of a blade-holding element having an undercut groove for holding the blades, said groove being widened for a relatively short distance for inserting the blades in the undercut groove, the widened portion of said groove having 70 serrated sides, said serrations extending transversely of the axes of rotation in a direction substantially normal to a radius of the blade-holding element intersecting therewith, a plurality of blades within the widened portion, and locking pieces for holding the 75 blades in the widened portion, said locking pieces having one side conforming in contour to the blade root and the other side thereof having complementary serrations fitting the serrations of the widened out portion and 80 adapted to be driven between the blade and the side of the groove in a direction for exerting a radial force inwardly of the blade-holding element.

10. In a turbine, the combination of a blade-holding element having an undercut groove for holding the blades, said groove being widened for a relatively short distance for inserting the blades in the undercut groove, the widened portion of said groove having 85 serrated sides, said serrations extending transversely of the axes of rotation in a direction substantially normal to a radius of the blade-holding element intersecting therewith, a plurality of blades within the widened portion, and locking pieces for holding the 90 blades in the widened portion, said locking pieces being in spaced relation to each other and having one side with serrations fitting the serrations of the widened portion and 95 adapted to be driven between the blade root and the side of the groove in a direction for exerting a radial force inwardly of the blade-holding element, and wedges between adjacent locking pieces.

10. In a turbine, the combination of a blade-holding element having an undercut groove for holding the blades, said groove being widened for a relatively short distance for inserting the blades in the undercut groove, the widened portion of said groove having serrated sides, said serrations extending transversely of the axis of rotation in a direction substantially normal to a radius of the blade-holding element intersecting therewith, a plurality of blades within the widened portion, and locking pieces for holding the blades in the widened portion, said locking pieces being in spaced relation to each other and having one side with serrations fitting the serrations of the widened portion and 100 adapted to be driven between the blade root and the side of the groove in a direction for exerting a radial force inwardly of the blade-holding element, and wedges between adjacent locking pieces.

11. In a turbine, the combination of a rotor provided with a circumferentially-extending 105

undercut groove for holding a row of blades and said undercut groove having on one side thereof a recess or widened portion for the insertion of blades therein, a row of blades inserted in the groove, a plurality of locking pieces in said widened portion of the groove and slidable circumferentially therein, each locking piece having interlocking engagement with the side of the widened portion of

the groove and the adjacent side of the blade 10 row, the total circumferential width of said locking pieces being less than the circumferential extent of the widened portion by an amount as great as the width of one blade.

In testimony whereof, I have hereunto subscribed my name this 26th day of August, 1924.

JAMES L. RAY.
